 Patent expires March 23, 1963

8 Claims. (Cl. 101—68)

1

The present invention relates to postal franking machines of the type comprising a printing mechanism for franking the letters (a franking mechanism), printing accumulating registers for printing the total value of the franking operations upon a pre-paid record strip sold by the post office, and a charging register indicating the number of charging procedures, that is, registering each charging of the machine with a pre-paid strip.

To further improve and facilitate the postal control some post office departments require that when the letters are posted a report be filed giving the setting of the total register and the charging register before and after a day's franking operations. Hitherto such reports were written by hand. However, in this way there has been no safeguard against errors. Moreover, the person making the records might be enticed to make fraudulent reports.

The invention has for its object to make possible a safer and better control of postal franking machines and to obtain this in a simple and reliable manner by a mechanism within the machine itself.

To the accomplishment of the foregoing and such other objects as may hereinafter appear, this invention consists in a franking machine comprising, in addition to the usual printing means set forth above, further printing means, such as printing hammers and type wheels, for printing the total value of the franking operations on a special daily-delivery report form before and after the franking operations of each day. Preferably, additional printing means are also provided for printing the total number of charging procedures upon said report form before and after the franking operations of each day. In this manner the statements on the daily-delivery report form will be correct under all circumstances.

One embodiment of the invention is illustrated, by way of an example, in the annexed drawing, in which:

Fig. 1 is a vertical cross section on the line I—I in Fig. 4, through a franking machine provided with mechanism according to the invention, this figure showing substantially only such parts as are essential for understanding the invention. In this embodiment the holder for the daily-delivery form is connected to the revolution stop of the franking shaft by means of a single revolution stop lever.

Fig. 2 shows a portion of a daily-delivery report form printed with the values of the total

2

register and the charging register before and after the franking operations of one day.

Fig. 3 shows a modification of the embodiment illustrated in Fig. 1.

Fig. 4 shows a part of the machine in a section on the line IV—IV in Fig. 1.

Figs. 5 through 17 illustrate a more complete disclosure of the franking machine substantially according to the embodiment of Figs. 1 through 3, provided with the device according to Fig. 3.

Fig. 5 is an end view taken in a plane parallel to the cross-section in Fig. 1 and near that end of the machine which in Fig. 1 is turned from the observer, viz. in a plane extending directly outside of the corresponding end-wall of the frame of the machine, but inside the outer housing or cover, certain parts being in a different position than in Fig. 1.

Fig. 6 shows a longitudinal elevation of said end-wall together with the parts on the outside of said end-wall, the outer housing being indicated by dashed and dotted lines, and the arrow V indicating the direction in which the end-view of Fig. 5 is seen.

Fig. 7 shows a cross section substantially in a plane parallel to the cross section in Fig. 1 but nearer the observer, the franking, registering, and printing means being omitted for the sake of clearness, and the sensing mechanism according to my copending patent application, Serial No. 681,971 being used in the lever connection from the holder of the daily-delivery form, to the main shaft.

Fig. 8 shows a cross-section substantially in the same plane as Figs. 1 and 3 but on a greater scale and illustrating substantially only the registering and printing means with adjacent elements.

Fig. 9 shows a cross-section in a plane parallel to the plane of Fig. 1 but nearer the observer of Fig. 1, said Fig. 9 illustrating merely a part of the mechanism.

Fig. 10 shows a fractional plan corresponding to Fig. 9, the line IX—IX indicating the plane along which the cross-section according to Fig. 9 is taken.

Fig. 11 shows a fractional longitudinal elevation, corresponding to Fig. 9, thus seen in the direction of arrow XI in Fig. 9.

Fig. 12 shows a cross-section substantially in a plane lying between the totalizer unit and the adjacent end wall, illustrating substantially only a locking device for the holder of the prepaid strip.

Figs. 13 and 14 are side and end views, re-

spectively, of a coupling wheel in one position of mounting.

Figs. 15 and 16 are corresponding views of said wheel in another position of mounting.

Fig. 17 shows a cross-section in a plane parallel to that of Fig. 8 but nearer the observer of Fig. 1, illustrating the ink ribbon feed on the outside of the totalizer unit.

Fig. 18 is a schematic elevation of the machine, indicating the position of some details in a symbolic manner, as well as the lines on which the different cross-sections are taken.

The main type of the franking machine for which the invention has been developed is of that well-known construction in which the total register is adapted to lock the franking machine when the franking operations have attained a certain maximum value corresponding to the prepaid value (the value of the strip sold by the post office) of the strip as set by the pin wheel, and the machine is unlocked when a new prepaid strip is inserted. Then the franking operations may be continued until this prepaid value is attained once more, and so on until the capacity of the total register has been fully utilized. Then the total register sets itself to zero position. The machine is not brought to the post office, but only the daily-delivery report form.

In Fig. 1 the reference numeral 1 indicates the main shaft of the franking machine which shaft is rotated for instance by a crank or handle 2, connected with said shaft by means of gearing 3 and 4. On the end portion adjacent to the handle 2, the shaft 1 carries a pin wheel 5 in which the pre-paid values may be set by means of the members 6. By this setting operation the pre-paid value in question is also set in the printing franking mechanism, mounted in a cylinder on the other end portion of the shaft, as indicated by 7, the setting of said members 6 being transmitted to the franking mechanism by means of levers or like means (not shown). The letters to be franked are moved through the machine on a table 12 mounted in the housing 15. When the shaft 1 is rotated the pin wheel 5 actuates counting or registering wheels 15, 16 by which the total value of the franking operations is set upon the type wheels 17. This total register 15, 16 is illustrated also in Fig. 4. This figure also shows the charging register 16' and the corresponding type wheels which are operated by the insertion of a pre-paid strip. Reference numeral 20 indicates a holder for the pre-paid strip or card. Numeral 22 indicates the ink ribbon and 28 indicates the printing hammer which cooperates with said type wheels 17. All these details are well-known to those skilled in the art and, therefore, only a brief description and illustration of the same is necessary.

On the shaft 1 a disc 30 is securely mounted, which disc is provided with a shoulder 31 co-operating with one end of a stop lever 32, that is, a revolution stop. This lever is rockably mounted on a stationary shaft 33 and has in its other end a slot 34 engaged by a pin 35. This pin is secured on a table 36 slidably mounted in the frame or housing 13 of the machine. On said table a blank form for a daily-delivery record can be inserted. By means of a handle 37 a shaft 38 can be rotated or rocked a definite angle up and down. Said shaft carries a disc 39. Two pawls 40 are rockably mounted on journals 41 on this disc. A tension spring 42 interconnecting the pointed ends of said pawls, yieldingly holds the other ends of the pawls in contact respectively with two pins 43 on the

disc 39. On a shaft 44 a printing hammer 45 is rockably mounted. The hammer, which is made as a double-armed lever, carries on one end a driving pin 46 and on the opposite end a striking pad 47, for instance, made of hard rubber. When the hammer is in its position of rest, it is, by means of a tension spring 48, yieldingly pressed against a stationary pin 49 mounted in the frame of the machine. On a stationary journal 50 a lever 51 is rotatably mounted, which lever carries a driving pin 52. The lever has its pointed end 53 resting against the lower edge of the table 36, this edge being bent inwardly. A tension spring 54 has one end connected to a pin 55 on the table 36 and the other end connected to a pin 56 mounted fixedly on the machine frame and which extends through a slot 57 in the table 36. Opposite an opening 60 in the table 36 and opposite the striking pad 47 of the hammer 45 the additional type wheels 62, 62' are mounted. Between the type wheels 62, 62' and the hammer 45 the ink ribbon 22 extends. These type wheels 62, 62' are set from the counting wheels 16, 16' through transmission wheels 63, 63' and 64, 64'.

The mechanism described operates in the following manner. When the details of the machine are in the positions shown by full lines in the drawing, the machine is in locked position, because the revolution stop lever 32 is in engagement with the shoulder 31 and prevents rotation of the main shaft 1. Thus, this is the position before the day's mail is franked. Now, a blank form 70 (Fig. 2) for a daily-delivery record is placed on the table 36 and the handle 37 is moved in the direction of the arrow A until it has reached the position shown by dot-dash lines in Fig. 1. By this motion one of the pawls 40, viz. the left one, engages the pin 46. Because this pawl rests against the pin 43 and, thus, cannot yield when pressed against the pin 46, the printing hammer 45 is operated, so that the value set upon the type wheels 62 is printed on the form 70 in the line B of column D, as shown in Fig. 2. The amount thus printed is the value of the franking operations before the day's franking and, thus, corresponds to the total value after the franking operations of the day before. In continuing the rocking motion of the handle 37 the same pawl 40 contacts also the lever 51, so that this lever is rotated in clock-wise direction in Fig. 1. By this motion the table 36 is displaced downwards into the position shown by dot-dash lines, while the pin 35 attached to the table drives the revolution stop lever 32, so that this stop is disengaged from the disc 30 and the shaft 1 becomes free to rotate. Now, after the printing, the day's franking operations are performed in the usual manner. It should be observed that, when the other (right) pawl 40 passes over the pin 46 of the printing hammer 45, the printing hammer is not operated because this pawl yieldingly pivots so as to pass the pin 46, this yielding motion not being prevented by the pin 43 of the pawl in question.

After the day's franking operations are performed, the handle 37 is returned to the initial position shown by full lines, this movement of return being carried out in a direction opposite to the arrow A. In the first part of this movement the right pawl 40 contacts the pin 46, so that the value now set on the type wheels 62, is printed on the daily-delivery record. Because this record sheet, by the displacement of the table, has been advanced a short distance, this second printing

operation is effected in the line C in Fig. 2, thus, for instance, below the preceding printing operation in the line B. Then, the parts return to their initial positions and the machine again is in locked position. Thus, the difference of the amounts printed in the lines C and B, makes the total franking value consumed in the day's franking operations. The printed form is, together with the day's mail, delivered to the post office, which, thus, reliably can verify that correspondence exists.

The machine, in addition to the franking printing mechanism and the total value of franking printing mechanism, is provided with, further printing mechanism 82' indicating the position of the charging register. This third printing mechanism prints in the column E in Fig. 2 and indicates the number of charging procedures, that is the charging of the machine with pre-paid strips sold by the post office. Thus, the post office also can verify that no unauthorized manipulations in the loading have been made.

Instead of the pawl-transmission mechanism hereinbefore described, cam discs may be used to operate the printing hammer and the table, as shown in Fig. 3. In this modification the shaft 38 is always rotated in the same direction (arrow A'), for instance by means of a knob (not shown), and carries two cam discs 39', 39''. The cam disc 39' engages the pin 46 and operates the printing hammer 45. The cam disc 39'' controls the table 36 over the roller 52', the lever 51, the journal 50 and the second lever 51''.

In Figs. 5 through 17 which comprise a more complete disclosure of the machine to which the present invention relates, corresponding details are provided with the same reference numerals as in Figs. 1, 3 and 4.

The machine has a main locking device comprising a key lock 75 (Figs. 5 and 6) arranged on one end wall 76 of the machine frame. In closed position, as shown in Fig. 5, the shaft 77 of the handle 2 is held over a link 78 and a dog 79 engaging the toothed disc 3 on the shaft 77. By means of a key (not shown) the main lock 75 is unlocked, the dog 79 disengaging the toothed disc 3 against the action of the spring 81. Reference numeral 82 indicates a device serving to prevent rotation of the main shaft 1 in reverse direction.

Figs. 5 and 6 illustrate also the holder 20 for the pre-paid strip extending through a slot in the end-wall 76 and in the cover 83, as well as operative means 84 for printing the pre-paid strip and operative means 85 for printing the daily delivery form. Said two operative means are actuated by one and the same key-like handle 37' of the means 85 as shown in Figs. 5 and 6, or on the operative shaft 88 of the means 84. The shaft 88 carries a curved disc 89 (Figs. 8 and 12) actuating the printing hammer 90 for the pre-paid strip. Both shafts 38 and 88 have positioning discs 91 and 92, respectively, cooperating with spring-pressed stop elements 93 and 94, respectively.

As will be seen from Figs. 7 and 8, compared with Fig. 1, the lever connection from the table 36 to the main shaft 1 of the machine is not made over one single lever, viz. the revolution stop lever 32 in Fig. 1, but the lever 51' of Fig. 3 is coupled with a blocking member 96 cooperating with the operative elements 97 of the sensing mechanism described and illustrated in my co-pending patent application, Ser. No. 681,971, filed July 8, 1946,

said elements 97 being adapted to release the revolution stop disc 38 after a letter has been introduced into the machine, as described in said co-pending application. However, no letters must be franked until the first printing has been made upon the daily delivery note, and therefore the blocking element 96 is adapted to prevent swinging motion of the rocker 98 of the sensing mechanism (corresponding to rocker 16 in said co-pending application) when the table 36 is in position of start, but to allow such swinging motion when the table 36 is in its displaced position. In Fig. 7 the position of start is indicated by dot and dash lines, the table 36 being in its lower position. By this the first printing of lower value will be obtained in a line below the second printing of higher value, and not as shown in Fig. 2.

The swinging motion of the rocker 98 is blocked also when no pre-paid strip is in the machine or when the value of a pre-paid strip has been consumed, thus also in dependence of the totalizer. An element for such blocking action is shown at 101 in Fig. 9. Said element 101 is made as an arm attached to one end of a sleeve 99 mounted on the shaft 99'. On the opposite end of said sleeve is attached a second arm 102, connected to one end of a link 103, the other end of which is connected with an actuator 104. This actuator 104 is at shoulder 105 operated from the totalizer over the coupling wheel 106 to lower the blocking element 101 from the position shown into the blocking position when the totalizer has attained the maximum value of the pre-paid strip. When a new pre-paid strip is inserted into the machine, the blocking element 101 is again moved from the blocking position by any suitable actuating system, for instance connected to the lower end 107 of the actuator 104 and operated from the holder 20. The lever 103 has two positioning recesses 108 corresponding to the two positions of the blocking element 101 and cooperating with the positioning means 109. The elements 103, 104, 106 and 109 are mounted in a plate 110 carried by a bar 111 and the shaft 112 of the wheels 15 of the totalizer.

Said first-mentioned arm 101 has also a vertical projection corresponding in shape to the arm 102 and connected to one end of a second link 115, the other end of which is connected with one arm 116 of a double-armed lever, the other arm 117 of which is adapted to cooperate with a stop disc 118 securely mounted on the shaft 88. The arrangement is such that rotation of the shaft 88 and thus printing on the pre-paid strip is prevented when the blocking element 101 has moved from blocking position, but rotation of the shaft 88 is allowed when the totalizer has moved the element 101 into blocking position. Said double-arm lever 116, 117 carries also a "signal" element 119 serving to indicate, in one position, that a new pre-paid strip has been inserted into the machine, and that the value of this pre-paid strip has not yet been consumed, and in the other position that the value of the pre-paid strip has been consumed. In this last-mentioned position the shaft 88 can be rotated, whereby the value as set in the totalizer is printed upon the pre-paid strip and finally a projection 120 on disc 120 (Fig. 12) actuates a locking lever 121 for the holder 20 of the pre-paid strip, moving said lever from locking position and allowing a spring 122 to displace said holder 20 a short distance out of the machine. Now, the lever 121 is resting upon the edge of the holder 20 and is not in locking position.

Assuming that the machine has been unlocked by means of a key and that a new pre-paid strip is to be inserted in the machine, such new pre-paid strip is placed upon the holder 20 partly protruding through the end wall 76 as well as through the outer housing or cover 83. Now, the holder 20 is pushed into the machine by hand. At the same time the actuator 104 is acted upon at 107 to lift the blocking element from blocking position to the position as shown in Fig. 9. When the blocking element 101 is lifted also the indicator 119 is moved to a signaling position, showing that the machine is charged with a non-consumed pre-paid strip, and at the same time locking the shaft 88 over the disc 113, so that further rotation of the shaft 88 is prevented and no printing on the pre-paid strip can be effected. The details in question now are in the positions as shown in Figs. 9 and 12.

A form for the daily-delivery note is inserted on its table 36. It is assumed that the shaft 38 has been rotated to such a position that the table is in its lower position and the blocking element 96 is in blocking position. Now, by means of the removable handle 37' the shaft 38 is rotated through an angle of 180°. During this rotation first the total value of the totalizer is printed on the note (printing hammer 45 being operated from one projection on the cam disc 39') and then the table is moved upwards (the cam disc 39" allowing the table to slide upwards under the action of its springs). During this movement the blocking element 96 is lifted from blocking position to the position as shown in Fig. 7, not preventing oscillation of the rocker 98 of the sensing mechanism.

Now letters may be inserted for franking the same. When a letter is introduced, the revolution stop disc 30 on the main shaft 1 is released by means of the sensing mechanism as indicated in Fig. 7 and clearly described and illustrated in my said co-pending application. When so many letters have been franked that the total of all franking values amounts to the value of the pre-paid strip, for instance \$100 (the totalizer thus showing \$100 more than before the franking), the corresponding counting wheel 15 actuates the coupling wheel 106 which operates the members 104, 103, 102, 101 to depress the element 101 into the blocking position, so that oscillation of the rocker 98 of the sensing mechanism is prevented. At the same time the indicator 119 is moved to a position signaling that the pre-paid strip is consumed, and in which the shaft 88 is released.

Now the removable handle 37' is placed upon the shaft 88 and this shaft with the curved disc 89 is rotated. By this motion first the printing hammer 90 is actuated, so that the amount of the totalizer is printed on the pre-paid strip, and then the stop lever 121 is released by the disc 120, so that the holder 20 of the pre-paid strip is (under the action of the tensioned spring 122) moved a distance out of the machine. Now, the consumed pre-paid strip can be removed and a new pre-paid strip can be placed on the holder 20 which then is inserted into the machine, as already described.

When all letters of the day's mail have been franked, the handle 37' is placed upon the shaft 38 and is turned through an angle of further 180°, whereby first the amount of the totalizer is printed on the daily delivery note and then the table 36 is moved downwards, the blocking element 96 being depressed into the blocking position. The table 36 and the associated parts remain in this

position until the letters of the next day's mail are to be franked. Thus, the machine cannot be used until the first printing has been made upon the note.

The coupling wheel 106 has ten teeth on one of its two end sides but only one tooth on the opposite end side. Either end side is used as transmitting element. As will be seen from Figs. 13, 14, 15 and 16, the coupling wheel is composed of a disc 130 having one tooth 131, and a gear ring 132 having ten teeth 133. In Figs. 13 and 14 the actuator is engaged by the ten-teeth side, and the blocking element 101 is operated each time the amount of \$100 is attained. By reversing the wheel 106, as shown in Figs. 15 and 16, the one-tooth side can be brought into position of use, and the blocking element 101 can be actuated by the amount of, for instance, \$500. Of course, in this case the amount of \$500 must be paid for each strip.

The feeding mechanism for the ink ribbon 22 is illustrated in Fig. 17. The ink ribbon 22 extends from the reel 140 over the rollers 141, 142, 143 to the reel 144. The reel 144 is provided with a toothed disc 145 which is rotated one step each time the printing hammer 45 is operated. This step-by-step rotation is effected from the printing hammer 45 over an arm 147 rigidly connected with hammer 45, and a link 148 adapted to rock a swingable support 149 for the pawl 150. The pawl mechanism 151 serves to prevent reverse rotation of the reel 144.

What I claim is:

1. In a machine for printing franking values directly on letters inserted into the same, comprising, in combination, operating means for the franking mechanism, a holder for a pre-paid strip, an accumulating register for the total postage value of the franking operations, type elements mounted on one side of said holder and connected with said accumulating register to be set by the same, a second holder for a daily delivery report form, additional type elements mounted on one side of the second holder and connected with said total accumulating register to be set by the same, pressing means mounted on the opposite side of the first holder to cooperate with the first-mentioned type elements to print the total value of the franking operations on said pre-paid strip, additional pressing means mounted on the opposite side of the second holder to cooperate with the additional type elements to print the total value of the franking operations on said daily delivery report form, and operating means for said additional pressing means.

2. In a machine for printing franking values directly on letters inserted into the same, comprising, in combination, operating means for the franking mechanism, a holder for a pre-paid strip, an accumulating register actuated by the franking mechanism for the total postage value of the franking operations, type elements mounted on one side of said holder and connected with said accumulating register to be set by the same, a second holder for a daily delivery report form, additional type elements mounted on one side of the second holder and connected with said total accumulating register to be set by the same, pressing means mounted on the opposite side of the first holder to cooperate with the first-mentioned type elements to print the total value of the franking operations on said pre-paid strip, additional pressing means mounted on the opposite side of the second holder to cooperate with the additional type elements to print the total

value of the franking operations on said daily delivery report form, operating means for said additional pressing means, and means interconnecting the operating means for the franking machine and the operating means for the additional pressing means for locking the former when the latter is in one position and unlocking it when in another position.

3. In a machine for printing franking values directly on letters inserted into the same, comprising in combination, operating means for the franking mechanism, a holder for a pre-paid strip, an accumulating register responsive to actuations of the franking mechanism for registering the total postage value of the franking operations, a second accumulating register for registering the total number of pre-paid strip charging operations, that is, the number of insertions of such pre-paid strips into the machine, type elements mounted on one side of said holder and connected with said accumulating register to be set by the same, a second holder for holding a daily delivery report form, additional type elements mounted on one side of the second holder and connected with said total accumulating register to be set by the same, other additional type elements mounted on said side of the second holder and connected with said charging register to be set by the same, pressing means mounted on the opposite side of the first holder to cooperate with the opposed type to print the total value of the franking operations as well as the total number of charging procedures on said daily delivery report form before and after the franking operations of each day, operating means for said additional pressing means, and means interconnecting the operating means for the franking mechanism and the operating means for the additional pressing means for locking the former when the latter is in one position and unlocking it when in another position.

4. In a machine for printing franking values directly on letters inserted in the same, comprising in combination, operating means for the franking mechanism, a holder for holding a pre-paid strip, an accumulating register responsive to actuation of the franking mechanism for registering the total postage value of the franking operations, a second accumulating register for the total number of pre-paid strip charging operations, that is, the number of insertions of such pre-paid strips into said machine, type elements mounted on one side of said holder and connected with said accumulating register to be set by the same, a slidable holding table for a daily delivery report form, additional type elements mounted on one side of said slidable holding table and connected with said total accumulating register to be set by the same, other additional type elements mounted on said side of said slidable holding table and connected with said charging register to be set by the same, pressing means mounted on the opposite side of the first holder to cooperate with the opposed type to print the total value of the franking operations on said pre-paid strip, additional pressing means mounted on the opposite side of said slidable holding table to cooperate with the opposed type to print the total

value of the franking operations as well as the total number of charging procedures on said daily delivery report form before and after the franking operations of each day, a handle coupled with said additional pressing means and said slidable holding table, to operate said additional pressing means and subsequently to displace said slidable holding table, when manipulated before the franking of each day, and again to operate said additional printing means and subsequently to allow return movement of said slidable holding table, when manipulated after the franking of each day, and a lock connected with said handle for locking the franking machine operating means when said handle is manipulated in one direction and unlocking said operating means when said handle is moved in the other direction.

5. A franking machine as claimed in claim 4, and in which the lock comprises a stop lever connected with said handle, said stop lever being in its locking position until said additional pressing means has been operated by the manipulation of said handle before the beginning of franking each day.

6. A franking machine as claimed in claim 4, and in which the lock comprises a stop lever connected with said slidable holding table and is in its locking position when said table is in its initial position.

7. A franking machine as claimed in claim 4, and in which the operating means for moving said slidable table includes a rotary member connected with said handle, two rockable pawls mounted on said rotary member, an actuating arm on said additional pressing means, arranged in the path of movement of said pawls to be operated by the same, an actuating lever for said slidable holding table, also arranged in the path of movement of said pawls to be operated by the same, a stop attached to said rotary member, to fix one of said pawls when said rotary member is rotated in one direction, a second stop attached to said rotary member, to fix the other of said pawls when said rotary member is rotated on the opposite direction, and a spring connected with said pawls, to hold each pawl yieldingly in contact with one of said stops.

8. A franking machine as claimed in claim 4, and in which the operating means for the additional pressing means includes two cam discs, an actuating arm on said additional pressing means, said arm engaging with one of said cam discs, and an actuating lever for said slidable holding table, said lever engaging with the other of said cam discs.
